UNITED STATES PATENT OFFICE.

EDWARD E. MURPHY, OF WINCHESTER, MASSACHUSETTS.

CARBONATING APPARATUS.

1,272,298.

Specification of Letters Patent. Patented July 9, 1918.

Application filed May 5, 1917. Serial No. 166,732.

To all whom it may concern:

Be it known that I, EDWARD E. MURPHY, a citizen of the United States, residing at Winchester, in the county of Middlesex and 5 State of Massachusetts, have invented new and useful Improvements in Carbonating Apparatus, of which the following is a specification.

This invention relates to apparatus for 10 charging water, or other liquid, with carbonic acid, or other gas, preparatory to dispensing the charged or carbonated liquid, the liquid and gas being forced under pressure into a tank in which the liquid is 15 charged, and from which it is dispensed.

The invention has for its object, first, to 20 automatically maintain a practically uniform predetermined pressure in the tank by discontinuing the supply of water to the tank when the gas pressure therein rises to a predetermined degree, and resuming the supply when the gas pressure is reduced. Another object of the invention is to simultaneously control the supply of both liquid 25 and gas to the tank, the supply of both liquid and gas being automatically discontinued when the pressure rises, and resumed when the pressure is reduced.

To the above-mentioned ends the invention 30 is embodied in the improvements which I will now proceed to describe and claim.

Of the accompanying drawings forming a part of this specification,—

Figure 1 is a side elevation of a carbonating apparatus embodying my invention.

Fig. 2 is an elevation of a portion of the apparatus shown by Fig. 1, viewed from a different point.

Fig. 3 is a section on line 3—3 of Fig. 2.

Fig. 3^a is a view similar to a portion of Fig. 3, showing the gas valve opened.

Fig. 4 is a diagram illustration of the circuit, which includes the electric motor and a switch, hereinafter described.

Fig. 5 is a view partly in section, illustrating a somewhat different embodiment of the invention.

Fig. 6 is a section on and above the line 6—6 of Fig. 5.

Fig. 7 is a side elevation, representing a complete carbonating apparatus, including the embodiment shown by Figs. 5 and 6.

The same reference characters indicate the same parts in all of the figures.

12 represents a carbonating tank having means at its upper end for engagement with

a pipe line 13, connected with a pump P, (Fig. 7), which is driven by a motor M, preferably electric, to force water into the tank 12.

16 represents a valved outlet at the lower end of the tank, through which carbonated water is delivered as required. Gas is delivered to the bottom of the tank from a suitable source of supply, under pressure, 65 through a gas conduit including a pipe line 17.

In accordance with my invention, I provide controlling means actuated or governed by gas pressure in the tank for stopping the 70 motor and pump when the pressure rises to a predetermined degree, and starting the motor and pump when the pressure is reduced, the tank being provided with a control conduit 11, communicating with its bottom, through which water may be displaced 75 from the tank by gas pressure on the water in the tank, to a point outside the tank where the displaced water acts on motor-starting and stopping means, as hereinafter 80 described.

In the preferred embodiment of the invention, shown by Figs. 1, 2, and 3, the gas conduit also includes a pipe line 18, and a casing 19 having oppositely projecting threaded 85 nipples 20 and 21, engaged respectively with the pipe lines 17 and 18, the ducts 22 and 23 of said nipples being out of alignment with each other, as shown by Fig. 3. The casing 19 contains a valve chamber 19^a, one side of 90 which has an annular valve seat 24 surrounding a passage 19^b. The duct 23 communicates with the valve chamber 19^a, and the duct 22 communicates with the passage 19^b. A gas valve 25 is normally held against said 95 seat by a spring 26, and has a stem composed of a reduced portion 28 formed to permit gas to flow from one duct to the other when the valve 25 is opened, and a cylindrical portion 29 having a gas tight 100 sliding fit in a stuffing-box 30 forming a part of the passage 19^b. The casing 19 is extended to form a diaphragm chamber composed of sections 31, 32, between which is clamped a flexible diaphragm 33 attached 105 by a screw 34 to a plunger 35 which is movable in a guide 36 and is normally depressed by a spring 37 in said guide, the pressure of said spring being adjustable by means of a screw 38 and a spring abutment 39 (Fig. 2). 110 A lever 40 fulcrumed at 41 on the guide 36, passes through a slot 42 in the plunger

35 and is connected therewith by a pivot-
pin 43. One end of said lever is pivoted at
44 to an adjustable link 45 which connects
the lever with a single pole electric switch
5 S, the movable member of said switch being
shown at 47 in the diagram, Fig. 4. The
circuit including the switch, also includes
the motor M, and may include a manually
operable switch member 47^a. The switch S
10 may be of the well known Cutler-Hammer
construction. An upward movement of the
lever opens the switch to break the circuit
and stop the motor and pump, while a down-
ward movement closes the switch to close the
15 circuit and start the motor and pump. The
head 34^a of the screw 34 constitutes a projec-
tion adapted to contact with the gas valve
stem portion 29 and open the valve 25, when
the plunger and diaphragm are depressed.
20 The control conduit 11, which is preferably
a pipe line including separably connected
sections, as shown by Figs. 1 and 2, com-
municates with the chamber 31 below the
diaphragm 33, as shown by Fig. 3. When
25 the gas pressure rises in the tank water is
forcibly displaced by the gas pressure, and
is forced through the control conduit
against the diaphragm and raises the latter
and the plunger 35, thus raising the lever 40
30 and breaking the motor circuit. When the
pressure is reduced the spring 37 acts to de-
press the plunger and lever and close the
circuit. Other means, such as a weight,
35 may be employed as a yielding pressure de-
vice to yieldingly depress the plunger. It
will now be seen that provision is made for
automatically discontinuing the supply of
water when the gas pressure in the tank rises
40 to a predetermined degree, and resuming the
supply of water when the gas pressure is
reduced by the withdrawal of carbonated
water at the outlet 16, and by absorption of
gas by the water in the tank.

The supply of gas to the tank is automati-
45 cally discontinued by the closing of the gas
valve 25 by its spring 26 when the dia-
phragm and plunger are raised, and is auto-
matically resumed when the valve is opened
50 by the spring 37, which acts to depress the
plunger and diaphragm, and open the gas
valve, as shown by Fig. 3^a, the projection 34^a
in descending, contacting with the valve
stem portion 29. Provision is therefore
55 made for simultaneously controlling the
supply of water and gas to the tank. The
control conduit 11 is preferably provided
with an extension 11^a communicating with
the casing 11^b, of a pressure gage.

In the embodiment of the invention shown
60 by Figs. 5, 6, and 7, the supply of gas to the
tank is not automatically controlled by the
means above described. The supply of wa-
ter is however automatically controlled by
gas pressure in the tank. In the last-men-
65 tioned embodiment a control conduit 48 ex-

tends from the bottom of the tank to a niple 49 on a diaphragm chamber 50, the gas
conduit 17 being entirely independent.

The gas conduit 17 in each embodiment of
the invention is provided with a valve seat 70
51 (Fig. 5), and with a valve 52, preferably
spherical, adapted to be opened by the enter-
ing gas and closed by pressure in the tank.
The opening movement of the valve is lim-
ited by a stop 53. A nozzle 54 forming a 75
part of the gas conduit, and perforated at
its upper end, distributes the gas entering
the tank.

The adjusting screw 38 and spring abut-
ment 39 constitute a means for varying the 80
resistance of the spring 37 to displacement
of the diaphragm by the gas pressure in the
tank, and therefore determining the degree
of gas pressure required to start the pump.

The control conduit 11 constitutes an ele- 85
ment of tank-pressure-regulating means con-
trolled by variations of gas pressure in the
tank to render the pump inoperative when
the tank pressure rises, and cause the opera-
tion of the pump when the tank pressure is 90
reduced. Said control conduit may coöper-
ate with any suitable movable member
equivalent to the diaphragm 33, which is
movable in one direction by fluid pressure,
and is yieldingly moved by a yielding pres- 95
sure device in the opposite direction, said
movable member constituting another ele-
ment of said means.

In each embodiment of the invention the
spring 37 constitutes a yielding pressure de- 100
vice which is independent of the tank, the
controlling member embodied in the dia-
phragm 33 being movable in one direction
by an increase of gas pressure in the tank to
stop the pump, and in the opposite direction 105
by said independent yielding pressure device
to start the pump.

It will now be seen that the pressure of
gas in the tank acting on the water in the
tank to displace some of the water into the 110
control conduit, stops the pump, and that an
independent yielding pressure device starts
the pump. The described operation is not
dependent on the height and weight of a
body of water in the tank, and there is no 115
liability of the pump being stopped when
there is not sufficient gas in the tank to
properly impregnate the water. The dia-
phragm 33 and spring 37 may be located in
any desired position relatively to the tank, 120
and may be located at any height above the
tank to which water may be displaced
through the control conduit. The tank may
therefore be conveniently located in a lim-
ited space, in the cooler of a soda fountain, 125
the controlling means being located where-
ever desired outside the cooler. The rela-
tive arrangement of the tank and control-
ling means shown by the drawings is unim-
portant, and is thus shown only for con- 130

venience, the tank and the controlling means being connected only by the conduits 11 and 17 (Fig. 1), or by the conduit 48 in Fig. 5. These conduits may obviously be of any 5 length desired.

As implied in the foregoing description and in the following claims, I am not limited to the specific mechanism of the embodiments of my improvements shown by 10 the drawings, except as otherwise required in certain of the more limited claims.

I claim:

1. In carbonating apparatus, in combination, a carbonating tank, a motor-driven 15 pump connected with the tank to supply liquid thereto, means for delivering gas under pressure to the tank, and controlling means actuated by variations of gas pressure in the tank to stop the pump when 20 the gas pressure rises, and start the pump when the gas pressure is lowered, said controlling means including a member movable in one direction by an increase of gas pressure in the tank to stop the pump, and 25 a yielding pressure device, independent of the tank, for moving the said member in the opposite direction to start the pump.

2. In carbonating apparatus, in combination, a carbonating tank, a motor-driven 30 pump connected with the tank to supply liquid thereto, a gas conduit connected with the tank to deliver gas under pressure thereto, a gas valve in said conduit, and controlling mechanism actuated by variations of 35 gas pressure in the tank and adapted to simultaneously stop the pump and close said valve when the gas pressure rises, and to simultaneously start the pump and open said valve when the gas pressure is lowered, said controlling means including a member connected with the gas valve and movable in one direction by an increase of 40 gas pressure in the tank to stop the pump and close the gas valve, and a yielding pressure device, independent of the tank, for moving said member in the opposite direction to start the pump and open the gas valve.

3. In carbonating apparatus, in combination, a carbonating tank, means for delivering gas under pressure thereto, a pump connected with the tank to supply liquid thereto, an electric motor for said pump, and controlling means actuated by variations of gas pressure in the tank and including a switch in circuit with the motor, a member connected with the switch and movable in one direction by a rise of gas pressure to break the circuit and stop the 55 pump, and a yielding pressure device, independent of the tank, for moving said member in the opposite direction to close the circuit and start the pump when the gas pressure is lowered.

4. In carbonating apparatus, in combina-

tion, a carbonating tank, means for delivering gas under pressure thereto, a pump connected with the tank to supply liquid thereto, an electric motor for said pump, and controlling means actuated by variations of gas pressure in the tank and including a switch in circuit with the motor, a member connected with the switch and movable in one direction by a rise of gas pressure in the tank to break the circuit and stop the pump, and a spring adapted to move said member in the opposite direction and thereby close the circuit and start the pump when the gas pressure is lowered. 70

5. In carbonating apparatus, in combination, a carbonating tank, means for delivering gas under pressure thereto, a pump connected with the tank to supply liquid thereto, an electric motor for said pump, and controlling means actuated by variations of gas pressure in the tank and including a switch in circuit with the motor, a member connected with the switch and movable in one direction by a rise of gas pressure in the tank to break the circuit and stop the pump, a spring adapted to move said member in the opposite direction and thereby close the circuit and start the pump when the gas pressure is lowered, and means for regulating the force of said spring to vary the degree of gas pressure required to start the pump. 80 85

6. In carbonating apparatus, in combination, a carbonating tank, means for delivering gas under pressure thereto, a pump connected with the tank to supply liquid thereto, an electric motor for said pump, and controlling means actuated by variations of gas pressure in the tank and including a control conduit communicating with the bottom of the tank to receive liquid forced therefrom by gas pressure, a member movable in one direction by displaced liquid forced from the tank to stop the pump, a yielding pressure device, independent of the tank, for moving said member in the opposite direction to start the pump, a switch in circuit with the pump motor, and operating connections between the said member and switch. 100 105

7. In carbonating apparatus, in combination, a carbonating tank, a gas conduit connected therewith, a pump connected with the tank to supply liquid thereto, an electric motor for said pump, and controlling means actuated by variations of gas pressure in the tank and including a control conduit communicating with the bottom of the tank to receive liquid forced therefrom by gas pressure, a casing comprising a diaphragm chamber communicating with the control conduit, a diaphragm in the diaphragm chamber movable in one direction by displaced liquid forced from the tank to stop the pump, a plunger supported by 110 115 120 125 130

said diaphragm, a spring exerting pressure on said plunger to move the diaphragm in the opposite direction to start the pump, a switch in circuit with the pump motor, and operating connections between said plunger and switch.

8. In carbonating apparatus, in combination, a carbonating tank, a gas conduit connected therewith, a pump connected with the tank to supply liquid thereto, an electric motor for said pump, and tank-pressure-regulating means controlled by variations of pressure in the tank and including a control conduit communicating with the tank, a casing comprising a valve chamber, a diaphragm chamber communicating with the control conduit, a passage between said chambers, a part of said passage being formed as a stuffing-box, and gas ducts forming parts of the said gas conduit, one duct

communicating with the valve chamber and the other with said passage, a spring-closed gas valve in the valve-chamber adapted to close said passage and provided with a stem-extending through said passage into the diaphragm chamber, a portion of said stem being formed to permit a flow of gas through a portion of said passage, and another portion being packed by said stuffing-box to form a gas-tight joint, a diaphragm in the diaphragm chamber, a spring-pressed plunger supported by said diaphragm and having a projection adapted to contact with said stem and open the gas valve, a switch in circuit with the pump motor, and operating connections between the said plunger and switch.

In testimony whereof I have affixed my signature.

EDWARD E. MURPHY.
